CONTAINER WITH INCLINED FRONT OPENING AND CLOSURE MEANS THEREFOR

Filed Jan. 17, 1945

UNITED STATES PATENT OFFICE

2,422,594

CONTAINER WITH INCLINED FRONT OPENING AND CLOSURE MEANS THEREFOR

Jon Stengren, Forest Hills, N. Y.

Application January 17, 1945, Serial No. 573,197

4 Claims. (Cl. 312—10)

1

This invention relates to containers. Although the present invention may be embodied in containers for various articles or materials, it is particularly useful in respect to containers or albums for phonograph records.

One object of the invention is to provide a container which is particularly well adapted to be used as a phonograph record album.

Another object of the invention is to provide a container having a receptacle body and additional parts which, in the open condition of the container, cooperate with the bottom of the receptacle body to provide the container with a broad base. By reason of this construction, the container when closed can be of narrow width for economy in space or for convenience in carrying and handling and yet is not liable to tip over when the container is opened and is positioned so that its narrower dimension is at the bottom of the container on the surface of a table or other support.

A further object of the invention is to provide a phonograph record container or case which, when open, exposes the sides of the records so that the titles or other information on the labels of the records can be read without requiring the withdrawal of each record from its compartment.

A further object of the invention is the provision of a container which is well adapted for the attractive packaging of various articles or materials.

A yet further object of the invention is generally to provide a container, the construction of which is simple and inexpensive and which lends itself to the attractive display or merchandising of various articles or materials.

The above and other objects, features and advantages of the present invention will be fully understood from the following description, reference being had to the accompanying illustrative drawings.

In the drawings:

Fig. 1 is a perspective view of a container embodying the present invention, said container being in the form of a portable phonograph record case;

Fig. 2 is a perspective view of the container in the open condition thereof;

Fig. 3 is a vertical sectional view of the container in the closed condition thereof;

Fig. 4 is a transverse sectional view on the line 4—4 of Fig. 3;

Fig. 5 is a perspective view of a container embodying the present invention, the container being opened, and illustrates the embodiment of the invention in a container for use other than as a phonograph record case.

Referring now to the drawings in detail and first to the invention as illustrated in Figs. 1 to 4, the container 10 comprises a receptacle body hav-

2

ing a bottom 12, laterally spaced side walls 14 upstanding from bottom 12 and a rear end wall 16 also upstanding from said bottom. As here shown, side walls 14 of the receptacle body are planar members each in the form of an isosceles right triangle. Also, as here shown, bottom 12 and end wall 16 are planar members disposed in right angular relation. Correspondingly, the triangle of each side wall 14 has a right angle between its base 18 and its vertical side edge 20 as indicated in Fig. 1. Thus, as illustrated in Fig. 2, the front or upper edges 22 of side walls 14 of the receptacle body slant or are inclined downwardly from rear end wall 16 toward the bottom 12. The interior of the receptacle body between the lateral side walls 14 is sub-divided into a plurality of phonograph record compartments by means here shown as a plurality of laterally spaced planar partition members 24 positioned in said laterally spaced relation by interposed planar spacing members 26 and 28 positioned adjacent the bottom 12 and by interposed spacing members 30 adjacent the upper part of end wall 16. Further, it will be observed, that the outer edges of spacer members 26 and 30 and the adjacent edge portions of partition members 24 collectively form longitudinally spaced parts 32 of the front of the receptacle body, the other front parts of which are constituted by the edges 22 of side walls 14 and by the upper edge portions of the partition members 24 between longitudinally spaced parts 32. Thus, the front of the receptacle body and the front opening of said body slant downwardly from the rear end wall 16 toward the bottom 12.

It will be understood that when as here shown the container 10 is constructed for use as a record album or case, the width of each record compartment between adjacent partition members 24 is such that the record slidably engages the confronting surfaces of adjacent partition members. In Figs. 2 and 3, a phonograph record R, shown in dot-and-dash lines, is positioned within one of the compartments, and by reference to Fig. 3 it will be observed that the record is engaged at circumferentially spaced points by the spacing members 26, 28 and 30 of the companion record compartment or recess, and further it will be observed that a substantial part of the record, here shown as about half of the record, projects outwardly beyond the front of the receptacle body. This is a desirable, although not an indispensable, feature, since it enables the title or other data on the usual center label of the record to be observed without necessarily withdrawing the record from its particular compartment, especially in the case of the records in the outermost compartment or in a compartment adjacent one from which another record has been removed. It will be noted that although the opening to the

interior of the receptacle body is in a plane which extends upwardly from the bottom when the latter is in its normally horizontal position, the circular record disks can not move out of the receptacle through said opening since the spacing members 26 provide a barrier to such movement. On the other hand, the records can be easily removed from the recesses by raising said records to clear said barrier while the records are moved forwardly through said opening.

Container 10 is provided with closure means comprising laterally spaced parts 34 which in the closed condition of the container, illustrated in Figs. 1 and 3, extend forwardly beyond the front of the receptacle body. As illustrated, each part 34 has a planar side wall portion 36 which is of right isosceles triangular form and which in the closed condition of the container is in the same plane as the companion side wall 14 of the receptacle body. Thus, side wall 14 and the complementary side wall 36 of the companion part 34 together form the complete side wall of the container at each side thereof. Each part 34 is also provided with laterally projecting portions 38 and 40, the laterally projecting portions 38 and 40 of the two parts 34 abutting each other at their adjacent inner edges when the container is closed as illustrated in Figs. 1 and 4. Each part 34 is preferably dimensioned in relation to the companion side wall 14 of the receptacle body so that in the open condition of the container illustrated in Fig. 2, laterally projecting portions 40 are disposed at the bottom 12 in the plane thereof and form in effect continuations of said bottom in the same plane therewith, thus providing the container with a broad base, whereby to prevent the container from tipping over when the container is opened for access to the records in the compartments of the receptacle body. It will be noted that this is a desirable feature since the container can have a bottom which is comparatively narrow, said bottom being of greater length than width, so that the container can be of narrow width to allow a plurality of similar containers to be disposed in side by side relation in a comparatively small space, and yet when the individual container is used it is prevented from tipping over on its support since in the open condition of the container lateral portions 40 broaden the base of the container.

Parts 34 are movable from the positions which they occupy in the closed condition of the container to the retracted positions which they occupy in the open condition of the container, and in the latter positions side wall portions 36 of said parts are disposed laterally of the adjacent side walls 14 in abutting relation thereto. As here shown, part 34 is hinged to the companion side wall 14. While this hinged construction may be provided by any suitable type of hinge, it is here shown as constituted by strips 42 of cloth, tape or similar sheet material adhesively or otherwise secured to the adjacent marginal edge portions of the companion parts 14 and 34. While laterally projecting portions 38 and 40 of part 34 are here shown at right angles to each other and of flat planar form, the side wall 36 being triangular, it is within the scope of this invention to make each of the side walls 36 of a different peripheral contour. Also, while as here shown both parts 34 are movable, it is within the scope of the present invention to form one of said parts as a non-movable relation thereto, and it is within the scope of this invention to omit or decrease the

width of the laterally projecting portions 38 and 40 of one of the parts 34 with a corresponding increase in the width of said laterally projecting portions of the other of said parts 34 to compensate for such omission or decrease in width of the laterally projecting portions on said first mentioned part 34. It will be understood that when parts 34 are in the position illustrated in Fig. 1 they constitute closure means for the receptacle body as well as constituting portions of the opposite side walls of the container in the closed condition thereof. Further, it will be noted that lateral portions 38 and 40 constitute parts of the peripheral wall of the container, the other parts of said peripheral wall being constituted by bottom 12 and end wall 16.

Provision is made for holding movable parts 34 in closed condition. Any suitable locking or latching means may be provided for this purpose, but as here shown, the latching means comprises members 44 and 46 secured, respectively, to the lateral portions 38 of the two movable parts 34, and members 48 and 50 secured to said lateral portions, respectively, and pivotally connected to each other as indicated at 52. Members 48 and 50 define an opening in which members 44 and 46 are snugly engaged in the latched condition of the latching means. The hinge between parts 48 and 50 of the latching means is provided by a layer of fabric or tape 54 adhesively secured to the upper surfaces of said members. Also, as here shown, container 10 is provided with carrying handles 56 secured to the lateral portions of movable parts 34. It will be noted that said handles are positioned so that they do not interfere with the supporting feature of said movable parts when the latter are disposed in their retracted positions in which they broaden the base of the receptacle, as illustrated in Fig. 2.

The receptacle 10A illustrated in Fig. 5 is or can be of the same construction as that of container 10 as hereinbefore described, but it will be noted that in container 10A the partition members which sub-divide the interior of the container into a plurality of compartments are omitted and that the spacing members provided in container 10 are also omitted. Further, as illustrated in Fig. 5, the longitudinally spaced portions 32A of the front of the receptacle body, corresponding to front portions 32 of container 10, are formed in one piece with the laterally spaced side walls 14A which correspond to the side walls 14 of container 10. The movable parts 34A are or can be of the same construction as the movable parts 34 and are hinged to side walls 14A of the receptacle body in any suitable way as by the strips 42 illustrated in Fig. 1. Parts 32A preferably have the downwardly and rearwardly inclined surfaces 58A and 60A corresponding to the similarly inclined surfaces 58 and 60, respectively, of the spacing members 26 and 30 of the container as illustrated in Fig. 3. Also, if desired, container 10A may be provided with a part corresponding to the lower rear spacing members 28 as shown in Fig. 3 with respect to container 10.

The containers embodying the present invention can be made of any suitable materials or combinations of materials. For example, said containers can be made of cardboard, wood, metal, any suitable plastic, etc., or combinations of such or other materials. Further it will be understood that the outer surface of the container can be covered in any suitable way, for example, by fabric, paper, etc. which can be of

any desired ornamental character. It will be understood that the invention may be embodied otherwise than as herein shown or described and that certain features of the invention may be used without others, and that various changes 5 may be made in the containers of the present invention without departing from the underlying idea or principles of the invention within the scope of the appended claims.

Having thus described my invention, what I 10 claim and desire to secure by Letters Patent is:

1. A container comprising a body defining a receptacle, said body having a bottom, an end wall, and laterally spaced side walls upstanding from said bottom, the width of said bottom between said side walls being less than the front to rear length of said bottom, said receptacle having a front opening in a plane disposed transversely of said side walls, the plane of said opening being inclined upwardly toward the rear of said body, each of said side walls being in the form of an isosceles triangle with a right angle between the bottom and end wall of the container body, and closure members having sides coextensive with said side walls, respectively, and each hinged to one of said side walls along an edge, which is the hypotenuse of the triangular side wall and of the closure member hinged thereto, said closure members being movable from retracted positions to positions in which said members extend forwardly of said opening and form continuations of said side walls, said members having lateral portions which form the top and an end wall of the container, in said last mentioned positions of said members, said members when in their retracted positions being disposed in confronting surface relation with the adjacent side walls, respectively, and having their end-wall forming lateral portions extending outwardly therefrom, respectively, and positioned at the bottom of the receptacle body and forming lateral extensions of said bottom for broadening the supporting base of said receptacle body.

2. A container comprising a body defining a receptacle having a bottom, an end wall and laterally spaced side walls, each of said side walls being in the form of an isosceles triangle with a right angle between the bottom and end wall of said body, said receptacle having an opening in a plane disposed transversely of said side walls, said opening lying in a plane inclined upwardly and rearwardly from the front end of said body, and triangular shaped planar parts having sides coextensive with said side walls, respectively, and hinged to said side walls, respectively, along an edge which is the hypotenuse of the triangular side wall and of the part hinged thereto and movable from retracted positions laterally of said side walls, respectively, to positions in which said parts extend forwardly of said edges of the companion side walls, respectively, and form with said companion side walls rectangular planar members at the opposite sides of the container, said movable parts having lateral portions which abut each other in said last mentioned positions of said parts for covering said opening of the receptacle body.

3. A container comprising a receptacle body having a bottom, a rear end wall and laterally spaced side walls, each of said side walls being in the form of an isosceles triangle with a right

angle between the bottom and end wall of the body, means in said body sub-dividing the interior thereof into a plurality of narrow disk-receiving recesses disposed in side by side relation laterally of the body, said recesses having openings lying in a plane inclined upwardly and rearwardly from the front end of said body toward said rear end wall, the recesses being of such depth that portions of disks positioned and supported in said recesses project outwardly therefrom through said openings, and closure members positioned at the opposite sides of the container and extending forwardly and upwardly beyond said openings for enclosing the projecting portions of the disks, said closure members having sides coextensive with said side walls, respectively, and hinged to said side walls along an edge which is the hypotenuse of the triangular side wall and of the closure member hinged thereto, at least one 20 of said closure members having a part which is disposed in the plane of the bottom of the receptacle body and projects laterally from the companion side wall, when said one of the closure members is moved to its open position.

25 4. A container comprising a receptacle body having a rear end wall, a bottom, and spaced side walls, each of said side walls being in the form of an isosceles triangle with a right angle between the bottom and rear end wall of said body, means in said body sub-dividing the interior thereof into a plurality of narrow disk-receiving recesses disposed in side by side relation laterally of the body between said side walls, said recesses being open at the front of said body, the recesses being 30 of such depth that portions of disks positioned and supported in said recesses project outwardly therefrom through said open front of the receptacle body, the upper edges of said side walls slanting downwardly from said end wall toward 35 said bottom, and closure members positioned at the opposite sides of the container and extending forwardly of said front of the receptacle body for enclosing the projecting portions of the disks, said closure members having sides coextensive with said side walls, respectively, and hinged to said side walls along an edge which is the hypotenuse of the triangular side wall and of the closure member hinged thereto, for movement to open 40 positions in which said closure members lie adjacent and parallel to the companion side walls, respectively, said closure members having lateral portions which are disposed in the plane of said bottom of the receptacle when said closure members are in said open positions thereof.
